Werner Koch, Offenbach (Main), Germany, assignor to Faber & Schleicher Aktiengesellschaft, Offenbach (Main), Germany, a firm

Original application March 22, 1951, Serial No. 216,886, now Patent No. 2,756,995, dated July 31, 1956. Divided and this application June 21, 1956, Serial No. 592,972

Claims priority, application Germany March 30, 1950

11 Claims. (Cl. 271—50)

The invention relates to printing machines operating in registration to perform multiple printing operations on sheets of paper or the like and, more particularly, to transfer devices for transferring sheets between the machines without effecting the registration.

This application is a division of Patent No. 2,756,995, issued July 31, 1956.

There are various printing operations in which the printing of a pattern or the like is performed in successive steps on different machines. The different machines, are, for such operations, prepared to print in registration so that a unitary composite result is achieved, and it is therefore imperative that the material being printed upon be transferred between machines without interference with this registration.

Furthermore, there are many printing operations which require a format or pattern to be printed in exact registration upon sheets or cards. To meet this requirement of exact registration, it is essential that each sheet or card be transferred to the printing device with great precision.

Accordingly, an object of the invention is to provide improved means whereby material to be printed upon is fed into a printing device in controlled registration with the format or pattern.

In the co-pending application, Serial No. 216,886, there has been described a chain gripper system comprising a gripper support pivotally mounted upon a movable chain traversing the distance between printing devices. The function of the grippers mounted on the aforesaid support was to grip the material released from one printing device, to be conveyed by the chain with this material to a second printing device, and to deposit the material with a second printing device.

To effect registration, a finger was provided on the gripper support to operate in conjunction with a locating or guide finger on the impression cylinder which, in known manner, performed the printing operation. Further, resilient means were provided to force the two fingers into intimate contact when the transfer was to be effected.

It is to be noted, however, that in the co-pending application, the gripper support was affixed, although pivotally, to the chain of the system. Briefly, the invention is concerned with detachably supporting the gripper support by the chain or the like and the provision of means to move the gripper support independently of the chain or conveying means whereby an intimate meeting of positioning fingers is obtained. Advantageously, the invention provides for a registered operation which is independent of the means utilized for conveying material to a printing device.

Other objects and advantages of the invention will be noted in the following description and illustrated in the accompanying drawing, which disclose, by way of example, the principle of the invention and the best mode which has been contemplated of applying that principle.

2

In the drawing:

Figs. 1 and 2 illustrate, in side view, a preferred embodiment of the invention in different positions of operation, namely before and during transfer.

Fig. 3 is a front view of a portion of a gripper support illustrating particularly the mode of conveyance thereof.

Fig. 4 is a top view of the apparatus of Fig. 3.

Figs. 5 and 6 are diagrammatic representations further explanatory of the apparatus shown in Figs. 1—4.

Figs. 7 and 8 are diagrammatic representations of a second embodiment of the invention.

Figs. 9 and 10 illustrate, in side view, the second embodiment before and during transfer, and

15 Figs. 11 and 12 are respectively front and side views of a gripper support which can be used in connection with the second embodiment.

In the aforementioned co-pending application there were illustrated two spaced printing machines, each provided with a printing cylinder and grippers thereon and connected by a chain gripper system adapted for conveying sheets of paper between the printing machine.

20 In order that the transfer of each sheet of paper between the various grippers occur at the proper time, the invention provided for the movement of the grippers of the chain gripper system independently from the chains of that system when the grippers are in a position adjacent the printing cylinder.

One form of the invention is shown in detail in Figs. 30 1—4 and diagrammatically in Figs. 5 and 6. The grippers have been omitted from most of the figures for the sake of general clarity but it will be noted that these grippers are equally spaced from the associated fingers which are hereinafter described. The gripper support or carriage includes two bars 201 and 202 and is provided 35 with rollers 203 and 204 on which it runs between the rails 205 and 206. The gripper carriage is detachably connected with the chain 207 by a roller 208 which engages in a link 209 on the gripper carriage. On the 40 side of the carriage, the link 209 carries a roller 210. Further, an abutment or guide finger 211 is rigidly fixed on the side of the gripper carriage. A guide finger 213 is also rigidly fixed on the printing cylinder 212.

45 As long as the chain runs in a straight line (Fig. 5), the gripper carriage is coupled with the chain 207 by the roller 208 and the link 209. When, however, the chain runs up onto the chain drum (not shown) and its path is thereby curved, the link 209 (Fig. 6) drops because it is located on the chord of the two rollers 50 203 and 204. The connection between the gripper carriage and the chain 207 is thereby released.

55 In order to convey the gripper carriage during the revolving of the chain 217 about the chain drum, a special device is provided. A lever 215 is firmly fixed to the drum shaft 214 and on the hub of this lever is loosely mounted a forked lever 216. The forked lever 216 is connected with the lever 215 by a spring 217. The spring 217 pulls a nose 218 of the lever 216 against a stop, which is for example a set screw 219 on the lever 60 215.

65 On quitting the straight track between the rails 205 and 206, the roller 210 of the gripper carriage becomes placed in the fork of the lever 216, which drives the gripper carriage while the chain 207 is revolving about the chain drum.

70 As soon as the guide finger 213 of the printing cylinder 212 bears against the guide finger 211 of the chain carriage and thereby advances the chain carriage, the forked lever 216 detaches itself from the set screw 219 and the spring 217 pulls the gripper carriage with its guide finger 211 against the guide finger 213 of the printing cylinder 212. Through the co-operation of these two guide fingers,

the chain gripper system is thus brought during the transfer of the sheet of paper into an exact position relative to the printing cylinder 212. This generally occurs when the grippers are aligned between the centers of the cross-sections of the drum and cylinder.

The second embodiment of the invention, as seen in Figs. 7-12, corresponds in its fundamental method of operation to the first described construction. It differs chiefly by the means in which the gripper carriage is detachably connected with its guide chains.

In Figs. 7 and 8, during the straight course of the chain 303, the rollers 301 and 302 of the gripper carriage rest in cups 304 and 305 of a long chain link 306. On the gripper carriage there is a third roller 307 which corresponds to the roller 210 described for the first construction (see Fig. 4). The roller 307 lies in the pitch circle of the chain 303 and is guided in this pitch circle line around the chain drum by the forked lever 308.

On the revolving of the gripper carriage about the chain drum, the carriage is thus suspended in the forked lever 308 by means of the roller 307 and the rollers 301 and 302 are guided by an outer guide rail 309. The roller cups 304 and 305, which are connected with the chain by the long chain link 306 and which on the passage of the chain 303 onto the chain drum, come into a chordal position thereby become released from the rollers 301 and 302, so that the gripper support is detached from the chains.

The forked lever 308 is disposed, in the same manner as the forked lever 216 of the first embodiment of the invention so as to be loosely rotatable with respect to a lever 310 which is firmly affixed to the chain drum roller 311.

The spring 312, the nose 313, and the stop 314 correspond to the spring 217, the nose 218 and the stop 219 in the second form of construction.

On the gripper carriage, a guide finger 315 is rigidly mounted at one or both of the sides thereof. On the printing cylinder 316 is fixed a guide finger 317 for co-operation with the guide finger 315.

The method of operation on the transfer of the sheet of paper is the same as for the first form of construction so that it is unnecessary to repeat the description of the operation.

What is claimed is:

1. In a printing system provided with an impression cylinder and sheet grippers thereon, a sheet transfer device comprising a first finger rigidly fixed to the impression cylinder, grippers for conveying the sheet to the impression cylinder, a gripper support, a second finger rigidly fixed to said gripper support, and means for resiliently and detachably supporting said gripper support to urge said fingers into intimate contact whereby the sheet is transferred between grippers in exact registration with the impression cylinder, said gripper support comprising a roller and said means comprising a forked guide member for engaging and resiliently supporting said roller for urging said second finger into intimate contact with said first finger.

2. In a printing system provided with an impression cylinder, sheet grippers thereon, a chain adapted to convey a sheet to the impression cylinder, and a rotatable drum adjacent to the impression cylinder for driving the chain; a sheet transfer device comprising a first finger on said impression cylinder, grippers for gripping the sheet, a gripper support detachably supported on the chain for moving the sheet in accordance with the movement of the chain, a roller on said gripper support, a second finger on said gripper support for contacting said first finger, a lever rigidly coupled to the rotatable drum, and a forked guide resiliently coupled to said lever and being caused to move by said lever in substantial compliance with the rotation of the drum, said forked guide supporting and detaching said gripper support from the chain for moving said gripper support about the drum, said first and second fingers contacting with said gripper support sup-

ported by said forked guide, said forked guide resiliently urging said fingers into intimate contact.

3. A sheet transfer device as claimed in claim 2 wherein said gripper support comprises a pivot supporting said roller and bars pivotally spaced from said pivot for supporting said grippers on said gripper support, said transfer device further comprising means for engaging said roller with the chain.

4. A sheet transfer device as claimed in claim 2 comprising cups mounted on the chain and wherein said gripper support comprises a pivot supporting said roller, rods rigidly spaced and pivotable about said pivot for supporting said grippers, and auxiliary rollers on said rods detachably supported in said cups.

5. In a sheet transferring device wherein a sheet is transferred between first grippers mounted on a first cylinder and second grippers transported by chains around a second cylinder: substantially coplanar bars rigidly inter-connected and pivotally and detachably connected to the chains, said bars constituting a support for the second grippers, a first abutment on the first cylinder, a second abutment on the support, and resilient means adjacent the chains and the first cylinder for contacting and supporting said support to urge said abutments into close contact when the grippers are substantially on a line joining the centers of cross-sections of the two cylinders to locate the grippers with relation to each other for the transferring of the sheet.

6. In a sheet transferring device wherein a sheet of paper is transferred between first grippers mounted on a first cylinder and second grippers transported by chains around a second cylinder; rigidly inter-connected bars constituting a support for the second grippers, connecting means for pivotally and detachably connecting said support to the chains, an abutment on the first cylinder, another abutment on the support for contacting the first said abutment, and a resilient member adjacent the chain and said first and second cylinders for contacting and supporting said connecting means so that said abutments are forced into close contact when the grippers are substantially on a line joining the centers of the cross-sections of the cylinders to locate the grippers with relation to each other for transferring of the sheet.

7. A sheet transferring device comprising an impression cylinder, grippers mounted on said impression cylinder, a first abutment mounted on said impression cylinder, a drum, chains around said drum, a roller pivotally and detachably supported on said chains, outer bars rigidly affixed on opposite sides of said roller and constituting a carriage pivotable about said roller, second grippers mounted on the carriage, a second abutment mounted on the carriage, and resilient means adjacent said chains, said drum and said cylinder to contact said roller and remove said carriage from said chains and urge said abutments into close contact when the grippers are substantially on a line joining the centers of cross-sections of the two cylinders to locate the grippers with relation to each other for transferring of the sheet.

8. A sheet transferring device comprising an impression cylinder, grippers mounted on said impression cylinder, a first abutment on said impression cylinder, a drum, chains around said drum, a support, support means for detachably coupling said support to said chains, second grippers mounted on said support, a second abutment on said support, a lever rigidly coupled to said drum, a forked guide member resiliently coupled to said lever and being urged by said lever to rotate with said drum, said forked guide receiving and detaching said support from said chains to urge said abutments into close contact when the grippers are substantially on a line joining the centers of cross-sections of the two cylinders to locate the grippers with relation to each other for the transferring of the sheets.

9. A sheet transferring device as claimed in claim 8 comprising a spring resiliently coupling said lever and

said forked guide, a set screw on said lever and a stop on said forked guide for contacting said set screw whereby said lever transfers motion of said drum to said forked guide.

10. A sheet transferring device as claimed in claim 8 wherein said support means comprises a link mounted on said chains, said support comprising a roller detachably engaged by said link.

11. A sheet transferring device as claimed in claim 8 wherein said support means comprises cups mounted on said chains, said support being detachably supported in said cups.
